UNITED STATES PATENT OFFICE.

FRED GUNTHER, OF PERU, ILLINOIS

SILO SEAL.

Application filed October 29, 1925. Serial No. 35,558.

The primary object of the present invention is the provision of sealing means for preventing the fermentation and spoiling of ensilage.

In carrying out the invention I provide a sealing and compressing cap member vertically guided for gravitational sliding movement within a silo, and which includes means for preventing the entrance of air into the ensilage.

More specific objects of the invention are to provide a device of this character which may be manufactured with comparative economy, which is of simple, practical and rugged construction, which may be readily assembled within the silo, and which will be highly efficient in use.

With the above noted and other objects in view the invention consists in certain novel features of construction and combinations and arrangements of parts, as will be more fully hereinafter set forth and pointed out in the claims. The invention may be more fully understood from the following description in connection with the accompanying drawings, wherein

Fig. 1 is a fragmentary vertical sectional view through a silo, illustrating my improved seal in applied position.

Fig. 2 is a fragmentary plan view showing a portion of the sectional sealing plate.

Fig. 3 is a transverse sectional view on the line 3—3 of Fig. 2.

Fig. 4 is a top plan view of Fig. 1.

Fig. 5 is a side elevation of one of the members 24.

A device constructed in accordance with the present invention includes a weighted sealing cap resting directly on the top of the ensilage and serving to maintain the same in compressed and airtight condition. There is preferably associated with this sealing cap some vertically disposed guiding means on which the cap is gravitationally 45 slidable.

In the illustrated and preferred embodiment of the invention, the vertically disposed guiding means includes a rod 10 carrying on its lower end a relatively large and 50 heavy anchoring member 11 which may consist of an iron block or may be of other suitable construction. The cap like sealing member is formed of a plurality of connected sections 12, each of said sections being of approximately sectoral shape, and the sections co-operatively providing a disc-like con-

struction with a central opening through which the guiding rod 10 passes. As indicated in Fig. 3, the sections 12 are preferably lined on their under faces with tar paper 13, and the passage of air between the edges of adjacent sections is prevented by the use of radial arms 14 disposed under the adjacent edges of each pair of sections, and having their upper surfaces covered with tar paper or some similar medium 15 which co-acts with the under coverings of sections 12 to provide an effective seal. Covering the central opening in the sealing disc is a circular plate 16 having a central opening 17 therein to snugly accommodate the guide rod 10, and having the outer edge of its under side faced with tar paper 18, which rests on the inner edges of all of the sections 12. A sleeve 19 surrounds the guide rod 10 above the sealing cap, the lower end of said sleeve preferably resting on a pair of gaskets 20 which lie against the top of the plate 16. Supported on the top of the sleeve is a circular block 21 connected by series of struts 22, with anchoring blocks 24 secured upon the top of the sealing plate. Each anchoring block connects a pair of adjacent sections 12, said blocks being disposed at right angles to the radial axis of such sections.

Tie bars 25 preferably include threaded ends passed through openings 26 in the blocks 24 and secured by nuts 27. The inner ends of all the tie bars are hooked as indicated at 28 and engage ring member 29 loosely encircling a sleeve 19 above the plate 16.

From the construction as thus far described, it will be apparent that I have provided a sealing cap which is gravitationally 55 slidable on the guide rod 10 to effect compression of the ensilage. It is to be understood of course, that the anchoring member 11 and the guide rod are buried to a suitable depth in the ensilage while the same is being 100 stored.

A wide band member 29^a resting on the sealing plate, co-operates with the outer edge of the sealing plate and the wall of the silo to provide a trough, which may be filled with salt, earth, or other appropriate air excluding material 30 to prevent the passage of air between the silo wall and the outer edge of the sealing plate.

It will be evident that the sectional construction of the sealing plate permits it to be assembled within the silo, thereby eliminat-

ing the inconvenience of attempting to lift an extremely heavy sealing member into position in one piece. Under ordinary conditions the weight of the sealing plate or cap is sufficient to pack down the ensilage. I find however, that it is desirable when the sealing cap is first applied, and the ensilage is rather loosely packed, to use a coiled expansion spring 31 around the top of the 10 guide rod 10 above the block 21. By tightening a nut 32 to effect compression of the spring, the sealing cap is firmly pressed down against the ensilage, and a substantial initial pressure is had. The spring of 15 course will become inactive as the weight of the sealing cap gradually depresses the ensilage and compacts the same into a smaller space.

While I have shown a guide member 10 anchored in the material which is stored in the silo, it may prove desirable to provide a stationary vertical guide member at the center of the silo, such guide member being anchored in the ground.

25 While the embodiment of the invention illustrated is a preferred one, it will be evident that various changes and alterations might be made in the general form and arrangement of parts described, without departing from the invention. Hence I do not

wish to limit myself to the details set forth, but shall consider myself at liberty to make such changes and alterations as fairly fall within the spirit and scope of the appended claims.

35

I claim:

1. The combination with a silo of a relatively heavy sealing cap fitting within the same for compressing the ensilage therein, a band member resting on the sealing cap and defining, together with the outer edge of the cap and the wall of the silo, a trough 40 adapted to be filled with sealing material.

2. A sealing cap for silos comprising a flat sectional plate adapted to fit within the 45 silo and rest upon the ensilage therein, a central guide post, a sleeve mounted above the plate on the guide post, a block carried at the upper end of the sleeve, struts connecting the block and the outer edges of the sectional plate, and a series of radially disposed tie bars connected at their outer ends to the plate, and at their inner ends to a common anchoring member.

50 3. A device as described in claim 2 where-
in the anchoring member includes a ring encircling the guide post, and receiving the hooked inner ends of the tie bars.

55 FRED GUNTHER.
